UNITED STATES PATENT OFFICE.

HENRY L. SHAVER, OF COHOES, NEW YORK.

SUSPENDER-SECURING PIN.

SPECIFICATION forming part of Letters Patent No. 443,118, dated December 23, 1890.

Application filed December 14, 1889. Serial No. 333,732. (No model.)

To all whom it may concern:

Be it known that I, HENRY L. SHAVER, of the city of Cohoes, county of Albany, and State of New York, have invented a Combined Suspender-Button Loop and Securing Pin, of which the following is a specification.

My invention relates to an improved suspender-button loop that is arranged by construction to be used as a securing-pin, by which, when the suspender-button comes off the garment, the button-loop is adapted to be pinned into the waistband of the pants to thus connect the suspender-loop with the latter without a button. It often occurs that by a sudden muscular movement of the body or extra effort made in lifting or stretching a suspender-button will be torn from its fastening so as to inconvenience the wearer, and it is to adapt the suspender-button loop to make a temporary connection with the pants without a button that is the object of my invention.

Accompanying this specification to form a part of it there is a sheet of drawings containing four figures illustrating my invention, with the same designation of parts by letter reference used in all of them. Of these illustrations, Figure 1 shows one of a pair of suspenders with button-loops connecting the suspender with the pants by means of buttons. Fig. 2 shows one of the button-loops as connected to the waistband of the pants without a button. Fig. 3 is a perspective of a button-loop adapted to pin into the waistband of the pants, and Fig. 4 is a section taken through the metallic loop-strap into the eye-passage, of which the divided ends of the loop are inserted to connect the loop with the suspender-button straps.

The several parts of a suspender thus illustrated are designated by letter reference, and the function of the parts is described as follows:

The letter S designates the body-strap of one of a pair of suspenders; B, the buckle; C, the button-strap clamp; E, the eye of the button-straps; S², the latter, and H the clasp on the lower end of the button-straps, made with the tubular passage P.

The letter L designates the button-loop, 50 made with the wider upper loop part l' for its passage on over the button and the lower narrower loop part l² to draw on around the eye of the button where connected to the garment. This loop is made of wire, the ends E² 55 E³ of which are made to approach each other in a straight line at the top, where they may be sprung apart for insertion within the opposite ends of the passage P, made in the clasp H. One of these ends and that indicated at E³ is made sharp, so that when a button l² comes off the loop may be spread apart, so as to be drawn out of the passage P with its sharpened end E² forced through the waistband W, as shown at Fig. 2, then turned in 60 this pinned connection, so as to thread the lower loop part l² into the garment, when the upper flat ends E² E³ are sprung apart and entered into the passage P of the clasp H, in which condition the loop is firmly secured to 65 the fabric.

Having thus described my invention, what I claim, and desire to secure by Letters Patent, is—

The combination, with the clamp of a suspender-button strap, which clamp is made with a hinging tube-form passage, of a wire button-loop having V-form sides with the lower end adapted to connect with an attached button, with the upper ends of the loop bent 75 toward each other and adapted to be entered at opposite ends of the hinging-tube for connection, and one of the upper ends of the loop made to have a pin form and adapted to be drawn from out the hinging-tube and 80 threaded into a garment and then inserted in the hinging-tube, substantially as shown and described.

Signed at Troy, New York, this 21st day of October, 1889, and in the presence of the two 85 witnesses whose names are hereto written.

HENRY L. SHAVER.
